Patented Dec. 30, 1919.

FIG. 1.

FIG. 2.

FIG. 3.

WITNESS:

C. B. West.

INVENTOR.

Aaron Terry,

BY
Frank A. Cutler.

ATTORNEY.

UNITED STATES PATENT OFFICE.

AARON TERRY, OF SPRINGFIELD, MASSACHUSETTS.

AIR-PUMP.

1,326,620.

Specification of Letters Patent. Patented Dec. 30, 1919.

Original application filed March 12, 1919, Serial No. 282,172. Divided and this application filed June 13, 1919. Serial No. 303,869.

To all whom it may concern:

Be it known that I, AARON TERRY, a citizen of the United States of America, residing at Springfield, in the county of Hampden and State of Massachusetts, have invented a new and useful Air-Pump, of which the following is a specification.

My invention relates to means for agitating the air in heating systems for buildings, 10 and consists generally of a hollow cylinder having therein a diaphragmal member which opens and closes, and a piston arranged to operate in said cylinder and having a member which opens and closes, said 15 last-named member being similar to said first-named member, together with such other elements as may be necessary or desirable to make the pump complete and serviceable, all as hereinafter set forth.

20 This invention is a divisional part of my application for Letters Patent of the United States, Serial No. 282,172, filed March 12, 1919.

In a hot-air heating system, such as that 25 set forth in the aforesaid application, it is necessary to provide mechanical means to induce circulation, and the primary object of my invention is to provide such means in the form of a pump, which is highly practicable 30 and efficient for the purpose for which it is designed, and, at the same time, is comparatively simple and inexpensive in construction and operation.

Other objects and advantages will appear 35 in the course of the following description.

I attain the objects and secure the advantages of my invention by the means illustrated in the accompanying drawings, in which—

40 Figure 1 is a central, vertical section through a pump which embodies a practical form of my invention; Fig. 2, a cross-section through said pump taken on lines 2—2, looking in the direction of the associated arrow, Fig. 1, and, Fig. 3, a cross-section 45 through said pump, on lines 3—3, looking in the direction of the associated arrow, Fig. 1.

Similar reference characters designate 50 similar parts throughout the several views.

In the first view I show a fragmentary portion of an outer shell or casing 1, of an ordinary, hot-air furnace, and the base portion of an intake 4. A horizontal, intake 55 cylinder 5 opens at one end, at 6, into the

casing 1, and is closed at the opposite end by a cap 7. The intake 4 opens at the bottom, at 8, into the top of the cylinder 5 at some distance from the casing 1.

It is to be understood that the hot air 60 from the furnace, after circulating through the system above, returns through the intake 4 and the cylinder 5 to said furnace to be reheated. And the purpose of the present invention is to provide mechanical means in 65 the cylinder 5 to promote and accelerate the movement of the air through said cylinder into the casing 1, for reasons which are clearly apparent.

I will now describe the pump, which 70 includes the cylinder 5, in detail.

Rigidly attached to the walls of the cylinder 5, in spaced relationship, and between the openings 8 and 6, are two rings 9. These rings are crosswise of the cylinder 5, 75 inside, and four horizontal rods 10, arranged at equal distances from each other, are rigidly attached to said rings. Mounted to slide on the rods 10, and provided with a yielding packing-ring 11 to bear upon or 80 against the inside of the walls of the cylinder 5 and maintain a tight joint, is a piston 12. The right-hand ring 9 is provided with a flapper valve 13, which is hinged at 14 to a supporting member 15 secured to said 85 ring, and arranged to open toward the outlet 6. A similar valve, but given the numeral 16, is hinged at 14', to another plate 15', carried by the piston 12, and also arranged to open toward the cylinder outlet, 90 it being understood that said piston has an opening, as 17, therethrough, which is covered when said valve is closed. The diameter of the opening 17 is as large or larger than the internal diameter of either ring 9. 95 A cross-piece 18 extends across the opening 17 in the piston 12, and said cross-piece has a pair of lugs 19 on the left-hand side thereof in the center.

An electric motor 20 is mounted on the 100 cylinder 5 at the left of the intake 4. Connected with and driven by the motor 20 is a crank-shaft 21, which is journaled at the lower end in a bearing 22 attached to the bottom of the cylinder 5. A piston-rod 23 105 is connected at one end with the crank-shaft 21, and at the other end with the lugs 19 by means of a pin 24.

When the crank-shaft 21 is rotated by the motor 20, it causes the piston 12 to be re- 110

ciprocated, through the medium of the piston-rod 23. Each time the piston 12 advances in the cylinder 5 toward the casing 1, the back pressure of air on the valve 16 closes the same, and at the same time the force exerted on the air by the advancing members opens the valve 13, and the air which is immediately in front of the now closed piston receives an impactive blow 10 which drives it into said casing—see the dotted lines in Fig. 1 which represent the piston at the forward end of its stroke. The effect of the aforesaid blow is felt throughout the entire heating system, and circulation is promoted and stimulated thereby. Each time the piston 12 recedes, the forward pressure of the air which is in the cylinder 5 between the intake 4 and said piston 12 causes the valve 16 to open so that said piston 20 is enabled to reach the inner end of its stroke without material opposition from the air. At the same time the valve 13 is closed by gravity assisted by whatever little suction the piston 12 may produce in moving to the 25 inner end of its travel. Gravity is a factor also in the closing of the valve 16.

It is now plainly to be seen that the air in the heating system above the element herein shown and described receives, at every forward stroke of the piston 12, an impulse which tends to keep said air in motion, the cool air that enters the cylinder 5 from said system first receiving the impact from said piston and thus being urged forward into 35 the casing 1. Here the air rises, is reheated, and continues on its round again. As a result of forcing the air, which is heated, by the piston into the casing by means of said piston, the air behind the latter is drawn or 40 sucked forward. Thus the cool air is impelled forward by both a driving force and suction.

The piston 12, in Fig. 1, is represented in full lines at the inner end of its stroke, and 45 the valves 16 and 13 are represented in closed position in full lines and in open position by dotted lines. There is an instant at each end of the travel of the piston 12 when the valves 16 and 13 are both in closed position, but during the forward movement of said piston the valve 13 is opened, and during the rearward movement of said piston the valve 16 is opened, as hereinbefore explained.

55 Changes in the shape, size, construction, and arrangement of some or all of the parts of this pump may be made, in order to meet varying conditions and needs, so long as such changes do not exceed the scope of 60 what is claimed, without departing from the spirit of my invention.

What I claim as my invention, and desire to secure by Letters Patent is—

65 1. The combination, in an air pump, with a cylinder, annular members secured within

said cylinder, one of said members being provided with a valve, and supporting and guide members attached to said first-named members, of a piston mounted on said supporting and guide members, said piston being provided with a valve, and means to actuate said piston. 70

2. The combination, in an air pump, with a cylinder, annular members secured within said cylinder, one of such members being 75 provided with a flapper valve, and supporting and guide members attached to said first-named members, of a piston mounted on said supporting and guide members, said piston being provided with a flapper valve 80 which opens in the same direction as said first-named valve, and means to actuate said piston.

3. The combination, in an air pump, with a cylinder, rings secured within said cylinder, a flapper valve hinged to one of said rings on one side, and rods carried by said rings, of a piston having an opening therein and mounted to slide on said rods, a flapper valve hinged to said piston on the side thereof which enables it to swing open in the same direction as does said first-named valve, and means to actuate said piston. 90

4. The combination, with the furnace casing, and the intake of a hot-air heating system, of a pump comprising a cylinder opening into said casing and intake, a perforated piston arranged to be reciprocated in said cylinder between said casing and intake, said piston having a flapper valve hinged thereto 95 and adapted to cover the perforation therein, a ring in said cylinder between said piston and said casing, and a flapper valve hinged to said ring and adapted to cover the opening therein, said valves being arranged 100 respectively to close and open under forward pressure and open and close under back pressure, and means to drive said piston. 105

5. The combination of a casing, an intake 110 cylinder opening into said casing, a perforated piston adapted to be reciprocated in said cylinder, said piston having a flapper valve hinged thereto and adapted to cover the perforation therein, a ring in said cylinder between said piston and said casing, and a flapper valve hinged to said ring and adapted to cover the opening therein, said valves being arranged respectively to close 115 and open under forward pressure and open and close under back pressure, a crank-shaft in said cylinder, a rod connecting said piston with said crank-shaft, means to drive said crank-shaft, and an intake mounted on said cylinder beyond the outer limit of 120 travel of said piston. 125
